CLEANOUT DEVICE FOR STOVES

Emanuel F. Fales, Sr., Portsmouth, Va.

Application October 27, 1937, Serial No. 171,336

4 Claims. (Cl. 126—242)

My invention relates to clean out devices and more particularly to a type adapted to be attached to the clean out sleeves of oil burners or the like.

5 One of the principal objects of my invention is to provide a clean out device equipped with means whereby the same may be readily attached to the clean out sleeve of an oil burner or stove.

10 Another object of my invention is to provide a device of the above described character having means contained therein whereby the closure plug, fitting within the clean out sleeve of a stove or the like, may be, when detached from the stove, inserted in said device and the soot scraped therefrom.

15 A further object of my invention is to provide a device of the above described character which is simple in construction, each in attachment and economical in manufacture.

20 Other objects and advantages will be apparent from the following description, appended claims and annexed drawing.

25 Referring to the drawing wherein like reference characters designate like parts throughout the several views:

Fig. 1 is a perspective view of an oil burning heater illustrating my invention attached thereto.

30 Fig. 2 is a vertical sectional view of a portion of the heater illustrating the invention attached thereto, the closure plug being illustrated in dotted lines.

Fig. 3 is a perspective view of my invention.

35 Fig. 4 is a sectional view taken on the line 4—4 of Figure 2.

Fig. 5 is a side elevation of the body illustrating the modified form of handle.

In practicing my invention I provide a stove, 40 preferably of the oil burning heater type 5 illustrated in the drawing. Said heater is equipped with the usual burner assembly 6 having a lower chamber 7 in which soot is adapted to accumulate. The front 8 of the heater 5 is provided

45 with a hinged door 9 through which access is obtained to a clean out sleeve 10 terminating at the lower end in the chamber 7. Said sleeve is adapted to receive therein a closure plug 11, illustrated in dotted lines in Figure 2, having an inner face flush with the inner end of the sleeve 10. Said closure plug is provided on the side

50 thereof with a bayonet groove 11a for engagement with a pin 12 extending interiorly of the sleeve whereby said plug is maintained within 55 said sleeve. The outer end of the sleeve 10 is

fashioned with a flange 13 for abutting engagement with a similar flange 14 formed on the outer end of the closure plug 11. The foregoing construction illustrated and described is typical of one of many forms of oil burning heaters.

5 As heretofore stated, soot accumulates within the chamber 7, upon the inner face of the plug 11 and oftentimes pervades between the outer periphery of the plug and inner periphery of the sleeve to form a coating on said peripheries. 10 The soot is removed from the chamber 7 by removing the plug 11 and withdrawing the soot through the sleeve 10. Heretofore, in this operation it was necessary to hold a receptacle under the outer end of the sleeve and to subsequently scrape the soot from the end of the plug 11 by any appropriate means at hand, such as a knife or the like.

20 To eliminate these undesirable features I have provided a clean out device comprising a hollow cylindrical body 15 having a closed bottom 16 and an inclined apertured top 17. Adjacent the top 17 the upper wall of the body is segmented to form an aperture 18 for effecting communication with the interior of the body. The apertured top 17 is adapted to embrace the outer end of the sleeve 10 and secure a body thereto in a downwardly and outwardly extending position as clearly illustrated in Figure 2. Secured within the body adjacent the top is a scraper member 19 fashioned with oppositely disposed arms 20, one of said arms extending transversely of the body. The section of the scraper member between the arms 20 is fashioned with a scraper edge 21 and likewise the inner faces of the arms 30 25 are formed with scraper edges 22. The arms 20 are adapted to embrace the inner end of the plug 11 and position the same therebetween and on the scraper edge 21. Consequently, rotation of the plug 11 against the scraper edges will remove soot therefrom and said soot will be discharged into the body towards the closed bottom thereof.

40 When the clean out device is attached to the sleeve 10, as illustrated in Figure 2, the soot from the chamber 7 and on the inner periphery of the sleeve 10 may be readily removed and deposited within the receptacle, thereby preventing the same from being distributed over the floor or like support for the heater.

45 Secured to the upper end of the body is a pivoted bail 23 whereby the receptacle may be carried in a vertical position to prevent soot contained therein from being accidentally discharged 50 55

therefrom when said receptacle has been detached from the sleeve.

In Figure 5 the body is provided with a fixed handle 23a on the outer periphery thereof and 5 intermediate between the ends. By the use of this form of handle the body may be readily connected to the sleeve 10.

What I claim is:

1. A clean out receptacle for stoves, comprising, a hollow cylindrical body having an inclined apertured end face at one end adapted for connection about the end of a clean out sleeve of a stove, and a scraper member secured within said body adjacent said face, said member segmented 10 intermediate of the length thereof to form oppositely disposed arms adapted to embrace the end of a detached closure plug of a stove whereby said plug may be rotated between said arms to clean soot therefrom by said member.
2. A clean out receptacle for stoves, comprising, a hollow cylindrical body having an inclined apertured end face at one end adapted for connection about the end of a clean out sleeve of a stove, a scraper member secured within said body 15 adjacent said face, said member segmented intermediate of the length thereof to form oppositely disposed arms adapted to embrace the end of a detached closure plug of a stove whereby said plug may be rotated between said arms to clean soot therefrom by said member.

soot therefrom by said member, said body segmented at the top thereof to form an aperture whereby access may be had to said clean out sleeve and said closure plug inserted for engagement with said scraper member.

3. A device of the character described for use in connection with a stove equipped with a clean out sleeve having a closure plug, comprising, an elongated hollow cylindrical body fashioned with a closed bottom and an inclined apertured top 10 adapted to be secured to said sleeve whereby said body will extend outwardly and downwardly from said sleeve, and a scraper member secured within said body and adjacent said top and fashioned with arms adapted to embrace said plug when 15 detached from said sleeve in a manner whereby said plug may be rotated thereon to clean soot therefrom.

4. A clean out device for stoves of a type equipped with a clean out sleeve having a closure 20 plug, comprising, a hollow body fashioned with an apertured top adapted to be secured to the sleeve whereby said body will extend away from said sleeve, and a scraper member secured within said body and adjacent said top and adapted 25 to engage said plug when detached from said sleeve in a manner whereby said plug may be moved thereon to clean soot therefrom.
